DESIGN FOR AN OVERBOOT OR SIMILAR
ARTICLE

Leslie H. L'Hollier, Waltham, Mass., assignor to
The B. F. Goodrich Company, New York, N. Y.,
a corporation of New York

Application May 23, 1946, Serial No. 129,999

Term of patent 14 years

(CL. D7—4)

To all whom it may concern:

Be it known that I, Leslie H. L'Hollier, a citizen of the United States of America, residing at Waltham, in the county of Middlesex and Commonwealth of Massachusetts, have invented a new, original, and ornamental Design for an Overboot or Similar Article, of which the following is a specification, reference being had to the accompanying drawing, forming part thereof.

Of the drawing:

Fig. 1 is a side elevational view of an overboot embodying my new design, the overboot being shown with the cuff turned down;

Fig. 2 is a fragmentary elevational view of the reverse side of the overboot with the cuff turned

down, portions of the boot not shown having substantially the appearance shown in Fig. 1;

Fig. 3 is a side elevational view of the overboot of Fig. 1 with the cuff turned up;

Fig. 4 is a fragmentary elevational view of the reverse side of the overboot with the cuff turned up, portions of the boot not shown having substantially the appearance shown in Fig. 3;

Fig. 5 is a side elevational view of the overboot with the cuff turned up and contracted by the strap and buckle arrangement.

I claim:

The ornamental design for an overboot or similar article, substantially as shown and described.

LESLIE H. L'HOLLIER.
